(57) **CLAIM**

The ornamental design for an add-on monitoring module for an injection pen as shown and described.

DESCRIPTION

1. Add-on monitoring module for an injection pen

1.1 : Perspective

1.2 : Front

1.3 : Back

1.4 : Top

1.5 : Bottom

1.6 : Left

1.7 : Right

1.8 : Perspective

The dot-dash broken lines in the figures and the lower opacity areas within the dot-dash lines, show portions of the add-on that form no part of the claimed design.
